UNITED STATES PATENT OFFICE.

JAMES M. DODGE, OF PHILADELPHIA, PENNSYLVANIA.

MACHINERY FOR HANDLING COAL.

SPECIFICATION forming part of Letters Patent No. 446,814, dated February 17, 1891.

Application filed November 14, 1890. Serial No. 371,455. (No model.)

To all whom it may concern:

Be it known that I, JAMES M. DODGE, a citizen of the United States, and a resident of Philadelphia, Pennsylvania, have invented 5 certain Improvements in Machinery for Handling Coal or Analogous Material, of which the following is a specification.

My invention consists of improvements in the construction of ways or supports for conveying machinery used in piling coal or analogous material for storage purposes. Heretofore in this class of work two general plans have been adopted, the first being the erection of long and substantially horizontal ways 15 from which are suspended large buckets that are moved back and forth, receiving and discharging loads of coal intermittently, such ways being supported by upright frame-work or posts, which remain buried in the coal to a greater or less extent for a long period, said 20 supports being thus subjected to the deteriorating action of moisture, sulphur, &c., and interfering with the free use of devices for reloading the coal for shipment. The other 25 plan is that which I have shown in several of my coal-handling devices patented within the past few years, and which consists, mainly, in the use of an endless conveyer chain or rope provided with laterally-projecting flights 30 or scrapers adapted to feed coal regularly and continuously to the storage pile, the mechanism being supported by a pole or a mast and boom.

By the operation of this device a substantially conical pile is formed.

A pole support is open to the objections noted above, and a boom overcomes the difficulties only in the case of small piles, as it must be inclined at an angle with the horizontal not greater than the angle of repose of the material to be piled and cannot practically be made long enough and strong enough to span half of a large pile. Furthermore, in coal-piling outfits using a suspended chain 40 and flights it is often desirable to employ intervening plates to reduce the friction between the loaded flights or scrapers and the coal over which they travel, and as these plates are heavy and have to be carried over 45 the yielding coal and must be readjusted in case the pile settles from any cause it is desirable to provide some convenient means of

supporting an adjustable anti-friction plate or series of plates interposed between the flights or scrapers and the pile, besides rendering all parts of the machinery accessible for oiling, repairs, &c., and reducing the strain which would be exerted on the chain if the latter were suspended between wheels. 55

The object of my invention is to overcome 60 the difficulties and secure the desirable features described above.

To enable those skilled in the art to which my improvement relates to understand and practice the same, I will now proceed to describe my invention more fully, referring to the accompanying drawings, in which— 65

Figure 1 is a side elevation of a coal-piling apparatus, illustrating my invention. Fig. 2 is a top view of the same. Fig. 3 is a detail 70 view on a larger scale, showing a cross-section of a portion of the truss structure and illustrating the relation of one of the flights or scrapers to the supporting-ways. Fig. 4 is a view illustrating a portion of a truss with an- 75 other form of conveyer, and Fig. 5 is an enlarged longitudinal section of the conveyer and support shown in Fig. 1.

C is the conveyer chain or rope.

F F are flights or scrapers.

W' is the head-wheel or that around which the chain and flights pass at the upper end of the conveyer.

W² is a wheel at the bend or angle between the horizontal and inclined runs of the conveyer used to hold the chain down and prevent the draft strain from lifting it away from its work. 85

W³ is the tail-wheel of the conveyer, around which the chain and flights pass at the receiving end. 90

P is the pile of coal.

M and M' are masonry supports for the lower ends of a pair of trusses inclined in opposite directions at or about the angle of repose of the pile and connected at their upper or meeting ends, so as to constitute the legs of a sheers structure, G being the lateral guys to stay the sheers in an upright position, and R the rod or other connection between the feet of the sheers to prevent further spread. 95

In Fig. 3 the inclined ways or supports which carry the flights or scrapers are marked

S, and the attachment block by means of which the flight is fastened to the chain is A.

The operation will be largely understood from the above description and a reference 5 to the drawings. In the present instance the material is fed to the horizontal portion at any convenient point between W³ and W², and after it leaves the level at W² it is carried up by the lower run of the conveyer and discharged onto the pile at its various stages of 10 formation.

In handling coal which has large lumps and where the friction between the loaded flights or scrapers and the coal over which 15 they travel would be excessive it is desirable to use an adjustable intervening plate (or series of plates) to overcome the friction, and the construction of the truss furnishes supports for such a plate and also for the conveyer-flights, as will be seen in Fig. 3, where 20 the plate is represented at I, and is carried by ledges or angle-iron projections a, provided on the truss for the purpose. The form in which I prefer to make this plate and the 25 means for adjusting it I have fully described in another application filed by me May 12, 1890, Serial No. 351,539. This plate may be briefly described as a steel ribbon or belt, which is, as shown in Fig. 5, wound around a 30 drum b at or near the foot of the truss, along which the conveying machinery travels, and is arranged to be drawn up toward the upper end of the conveyer as the formation of the pile progresses, the ribbon being supported 35 on the ledges a in the truss frame-work, as described above, and adjustable lengthwise of the leg of the sheers, so as to form an advancing point of discharge to suit the requirements of the growing pile.

40 To make all parts accessible for oiling, repairs, &c., I attach to the side of the truss and about on a level with the conveying machinery a walk or stairway with a light hand-rail at the outside.

45 Of the two runs of chain and flights the lower or carrying run is sustained by the side supporting-ways S S, thus overcoming the strain which would result from the suspension of a long stretch of chain and flights 50 between the upper and lower wheels. The space between the lower ends of the side plates S provides for the discharge of the coal when the latter has been carried up to the top of the adjustable bottom plate I or to the 55 apex of the pile when said bottom plate is not used. The upper run of chain and flights is returned on guide-strips G', as shown in Fig. 1, or on idlers placed near enough together to prevent the strain of such long 60 stretches. The truss structure furnishes a support for these idlers when used, so that they do not require to be suspended by ropes or cables under great tension, as has been necessary heretofore.

65 In Fig. 1 I have shown my piling device as used in connection with a horizontal conveyer, and it is evident that the horizontal portion

could be extended to any desired distance or dispensed with altogether without affecting my invention, and it is also plain that the 70 driving power may be applied either at W' or W³, as the circumstances of the case may suggest. The sheer-legs are preferably provided with masonry supports, and the feet are preferably held from further separation 75 by a tie-rod R or other connection running under the pile and insulated from the effects of moisture, sulphur, &c., in any well-known manner, and the two legs of the truss are hinged at the apex as a matter of convenience 80 in construction and erection; but it is evident that various modifications of such details of arrangement may be adopted without departing from my invention.

I have shown my device as applied to the 85 style of coal-handling machinery which I have used most frequently—namely, that which employs an endless chain or cable provided with transverse flights or scrapers; but it is evident that I can use any other form of continuous conveyer—for instance, a screw conveyer, as shown in Fig. 4—supported at proper intervals by bearings suitably attached to the truss structure. The form illustrated in the drawings utilizes but one leg of the sheers; 90 but if circumstances should make it desirable to use both legs this modified form would of course come within the spirit of my invention, and, if desired, the sheers may be composed of more than two legs. 100

I have not considered it necessary to illustrate the various uses which could be made of my device.

In the claims I use the words "continuous forward-feed conveyer" to distinguish the 105 conveyer used by me from conveyers which carry a load to the pile and return for a new load before another load is discharged onto the pile—such, for instance, as a single bucket, which reciprocates between the point 110 of loading and the point of discharge or piling.

I claim as my invention—

1. In an apparatus for piling coal or analogous material, a sheer structure composed of legs arranged in respect to each other at or 115 about the angle of repose of the material to be piled, and also arranged to span the pile to be formed, with a continuous forward-feed conveyer carried by said sheer structure and adapted to form the pile under the sheers, 120 substantially as described.

2. In an apparatus for piling coal or analogous material, a conveyer-support inclined at or about the angle of repose of the material to be piled, and fixed in this position, and an 125 endless conveyer traveling on said support and provided with flights, the lower run of the conveyer being the elevating one, substantially as set forth.

3. The combination of a conveyer-support 130 extending upward at or about the angle of repose of the material to be piled, a movable bottom for varying the point of discharge, and a continuous forward-feed conveyer for

carrying the material up the inclined plane to the said discharge-point, substantially as and for the purposes described.

4. In an apparatus for piling coal or analogous material, a stationary sheer structure composed of legs fixed in respect to each other at or about the angle of repose of the material to be piled, and also arranged to span the pile to be formed, masonry supports upon which the lower ends of the legs are fixed, and a continuous forward-feed conveyer carried by said sheer structure and adapted to form the pile under the sheers, substantially as described.

15 5. The combination of an inclined supporting structure with a continuous forward-feed conveyer supported throughout the length of its elevating portion by said structure, the latter having an open bottom to permit of the discharge of material from the elevating portion of the conveyer at advancing points throughout the length of the supporter, substantially as described.

20 6. The combination of the inclined supporting structure having side bearing-plates throughout its length and open at its center for the free discharge of material, with a continuous forward-feed conveyer supported by the side plates throughout the length of its

30 elevating portion, substantially as described.

7. The combination of an inclined supporting structure having side plates and movable bottom with a continuous forward-feed conveyer adapted to be supported throughout the

length of its elevating portion by said structure, substantially as set forth.

8. The combination of the sheers composed of legs inclined at or about the natural angle of repose of the material to be piled, and joined at their upper ends, with a conveyer 40 arranged to carry the material to be piled up one of said legs, and means for connecting the lower parts of the legs together, substantially as set forth.

9. The combination of the sheers having 45 legs inclined at or about the natural angle of repose of the material to be piled, and joined at their upper ends, an inclined plane on one of said legs, and a continuous forward-feed conveyer for carrying the material on 50 this incline plane to a point of discharge, substantially as set forth.

10. The combination of the sheers composed of legs inclined at or about the natural angle of repose of the material to be piled, a wheel at 55 or about the junction of the two legs, a wheel at the base of one of said legs, an endless-chain conveyer, flights thereon, and a guide supported by the leg for the return run of the endless chain, substantially as specified. 60

In testimony whereof I have signed my name to this specification in the presence of two subscribing witnesses.

JAMES M. DODGE.
